UNITED STATES PATENT OFFICE.

EDWARD B. LOCKE AND JOHN P. MURRAY, OF DETROIT, MICHIGAN, ASSIGNEES, BY
MESNE ASSIGNMENTS, TO THE COMPUTING SCALE COMPANY, OF DAYTON, OHIO, A
CORPORATION OF OHIO.

PIVOT MOUNTING FOR WEIGHING SCALES.

Application filed October 30, 1920. Serial No. 420,636.

To all whom it may concern:

Be it known that we, EDWARD B. LOCKE and JOHN P. MURRAY, both citizens of the United States of America, both residing at Detroit, in the county of Wayne and State of Michigan, have invented certain new and useful Improvements in Pivot Mountings for Weighing Scales, of which the following is a full, clear, and exact description.

10 In the manufacture of weighing scales, one of the most troublesome operations is the sealing of the levers and other elements embodying pivots. Notwithstanding the fact that the designer of the scale may have located the pivots at the theoretically correct locations, the assembler will frequently find that the levers do not balance properly and it becomes necessary to adjust the pivots in some manner to bring the levers to proper balance.

15 This operation which is known as sealing is usually carried on by hammering the pivots so as to bend them slightly. Thereafter it may be necessary to regrind the pivot edges. Since this kind of sealing is usually a "cut-and-try" operation, such operation requires particularly skilled workmen, and even with them the operations are time-consuming and add greatly to the assembly expense.

20 The present invention has for its objects the provision of a pivot mounting which will facilitate the proper locating of the pivots and also to provide a mounting which will be comparatively simple and inexpensive to manufacture.

In the drawings:

Figure 1 shows a scale lever embodying the improved pivot mounting.

25 Fig. 2 is an enlarged side view of the pivot portion of the lever.

Fig. 3 shows a top plan view of the parts shown in Fig. 2.

30 Fig. 4 is a detail perspective view of the notched bushing.

Fig. 5 is a perspective view of a knife-edge pivot.

35 Fig. 6 shows the knife-edge placed in the notch in the bushing prior to the final clamping operation.

In more detail, 10 represents a lever or scale element which is to be provided with a number of pivots. This element is drilled with straight round holes 11. The centers

of these holes are located upon the vertical 55 pivot center lines and are to one side of the range line of the lever as shown in Fig. 1. Within these holes are placed bushings 12, preferably made of brass and fitting the holes with a snug but slipping fit. Each 60 bushing is provided with a deep V-shaped notch 13 having the bottom thereof below the center of the bushing. The angle between the sides of this notch is slightly less than the angle between the sides of the knife-edge or pivot 14 (see Fig. 6). In assembling the parts the knife-edge pivots are slipped into the notches (Fig. 6) and these parts are then inserted into the holes in the lever. Thereafter set screws 15, which 65 are threaded into holes in the lever, are tightened. Each set screw bears down upon the arcuate top of the knife-edge and as the set screw is tightened the knife-edge acts as a wedge upon the bushing to spread it and 70 clamp it tightly in the hole in the lever.

75 Should it be found that the lever be out of balance and a change of pivot location be necessary, the assembler loosens the set screw and by means of pliers or other suitable tool 70 twists the knife-edge pivot to the left or right until the proper setting is obtained. Thereafter the set screw is tightened and the knife-edge pivot is again firmly retained in the position to which it has been set.

80 What we claim is:

1. An adjustable pivot mounting for a scale element comprising a scale element with a round opening therein, a notched bushing in said opening, a pivot carried in 85 the said notch, and means carried by the element and coacting with the pivot to wedge the same into the notch in the bushing and clamp the latter in the scale element.

2. An adjustable pivot mounting for a 90 scale element comprising a scale element with round openings therein adjacent the pivot center bushings in said opening, said bushings having V-shaped notches therein extending beyond the centers thereof, knife-edge pivots within said notches, and set screws carried by the scale element and coacting with the knife-edges to wedge the latter into the notches of the bushings whereby the bushings are spread and clamped in 95 position in the scale element.

3. An adjustable pivot mounting for a 100 weighing scale element comprising a notched

bushing mounted in said element and adapted to be rotatably adjusted therein, a pivot mounted in said bushing and having surfaces disposed at an angle to the surfaces of the notch, said pivot having an arcuate top portion and a set screw carried by the scale element and adapted to be advanced into contact with the arcuate top of the pivot whereby the latter acts as a wedge and spreads the bushing to prevent relative movement of the bushing and the scale element.

4. An adjustable pivot mounting for a scale element, comprising in combination, an apertured element, a bushing within said aperture and rotatably adjustable thereto, a pivot carried by said bushing and having a bearing edge eccentric to the bushing center, and adjustable retaining means for securing said bushing in position in the element, said retaining means being adapted to permit the knife-edge and bushing to be rocked to thereby displace the bearing edge of the pivot relatively to the scale element.

5. An adjustable pivot mounting for a scale element comprising a scale element with a round opening therein, a notched bushing in said opening, a pivot carried in said notch, and means carried by the scale element for spreading the notched bushing to thereby clamp the same in the opening in the scale element and for concurrently clamping the pivot in the desired position of adjustment.

6. An adjustable pivot mounting for a scale element comprising a scale element having a round opening therein, a notched bushing in said opening, a pivot carried thereby in said notch, and means including an adjustable device carried by the scale element for spreading the notched bushing to clamp the latter in the element and for retaining the pivot in the desired position of adjustment therein.

In testimony whereof we hereto affix our signatures.

EDWARD B. LOCKE.
JOHN P. MURRAY.
